T. COLSON.

CARTRIDGE FUSE.

APPLICATION FILED DEC. 2, 1918. RENEWED APR. 3, 1922.

1,419,226.

Patented June 13, 1922.

INVENTOR

Thomas Colson.

UNITED STATES PATENT OFFICE.

THOMAS COLSON, OF CHICAGO, ILLINOIS, ASSIGNOR TO CHARLES DAWSON, OF BELVIDERE, ILLINOIS.

CARTRIDGE FUSE.

1,419,226.

Specification of Letters Patent. Patented June 13, 1922.

Application filed December 2, 1918, Serial No. 204,996. Renewed April 3, 1922. Serial No. 549,252.

To all whom it may concern:

Be it known that I, THOMAS COLSON, a citizen of the United States, residing at Chicago, in the county of Cook and State of Illinois, have invented certain new and useful Improvements in Cartridge Fuses, of which the following is a specification.

My invention relates to cartridge fuses, and has for one of its objects the provision of a simple and efficient device of the character mentioned. A further object is the provision of a cartridge fuse in which the fusible member can be quickly and easily changed or renewed without the use of tools. Other objects will appear hereinafter.

An embodiment of my invention is shown in the accompanying drawing, forming a part of this specification, and in which—

Fig. 1 is a central sectional view of a cartridge fuse embodying my invention in operative position in a fuse plug and cut-out.

Fig. 2 is a perspective view of the body of my cartridge fuse.

Figs. 3, 4 and 5 are sections taken on lines 3—3, 4—4 and 5—5, respectively, of Fig. 1, of the cartridge fuse only.

Fig. 6 is a view similar to Fig. 5 showing a slight modification; and

Fig. 7 is a perspective view of an insulating tube adapted for use with my cartridge fuse.

Referring more particularly to the drawing, I have illustrated a cut-out or fuse socket 6 of standard Edison type having an electrical contact 7 in the bottom of a recess 8 therein, and a threaded shell electrical contact 9 on the side walls of the recess. Into said socket extends a fuse plug 10 which is provided with an electrical contact shell member 11 threaded in the contact 9 of the socket. An electrical conductor 12 extends from the contact 11 along the plug through an opening 13 in the latter and terminates in an electrical contact 14 on the bottom of a recess 15 in said plug 10. The fuse plug and cut-out or fuse socket shown indicate a suitable arrangement for cooperating with my fuse cartridge, but any other arrangement having suitable contact members capable of 50 clamping my cartridge fuse between them may be used.

The body portion 16 of my cartridge fuse is preferably cylindrical and of a size to substantially fit the recess 15 of the plug 10, as indicated in Fig. 1, but the relative diameters

of said body 16 and recess 15 may be formed so as to permit the insertion of a tube 25 of electrical non-conducting material, shown in Fig. 7, in said recess around said body. A longitudinal groove 17 is preferably formed 60 in the body 16 for a fusible member or link 18, but the groove 17 may be dispensed with where there is enough space between the body 16 and the sides of the recess 15 for the link 18. In one side of the body 16 I preferably 65 form a recess 19 which serves as an air space around the central portion of the fusible link 18.

At each end of the body 16 I provide a disc 20 which has a stem 21 extending substantially axially of said body through an opening 22 in the latter, into said recess 19. The end portions 23 of the stems 21 may be split and bent over, as indicated in Fig. 3, provided with heads 24, as indicated in Fig. 6, 75 or otherwise formed to prevent the removal of the stems 21 from said openings 22. The stems 21 are of sufficient length to provide spaces between the ends of the body 16 and the discs 20 for the ends of the fusible link 18. 80 Said link 18 may be an ordinary round wire fuse or have any other desired shape in cross-section.

A fuse link 18 is put in position by bending an end portion of a piece of fuse wire, or the 85 like, around one of the stems 21 substantially as indicated in Fig. 5, then laying a portion of such wire in the groove 17 bending another portion of the wire around the other stem 21, then finally breaking the wire off by bending 90 it back and forth a few times over the edge of the disc 20 on the last-mentioned stem 21. It will thus be seen that no tools are required for changing or renewing the fuse link 18 in the device.

In use, my cartridge fuse is clamped tightly between the contacts 7 and 14 by the plug 10 being screwed in the cut-out 6, or other similar arrangement. This clamping action holds the end portions of the fuse 100 link 18 tightly between the ends of the body 16 and discs 20, thereby insuring efficient electrical connections between contacts 7 and 14, discs 20, and fuse link 18.

I claim:—

1. A cartridge fuse comprising a body; discs spaced from the ends of said body; stems extending toward each other and movably associated with the body; retaining means at the adjacent end portions of the 110

- stems for engaging the body to limit movements of the discs away from the body; and a fuse wire having its ends extending between the ends of the body and said discs.
5. 2. A cartridge fuse comprising a body having a recess in its sides and perforations in its end portions opening into said recess; stems disposed loosely in said perforations; retaining means on the stems in said recess; 10 discs on said stems at the ends of said body; and a fuse wire disposed across said recess with its end portions extending around said stems between said discs and the ends of said body.
15. 3. A cartridge fuse comprising a body having a recess in one side and a perforation in each end extending to said recess; a disc at each end of said body; a stem attached to each disc extending through one of said perforations into said recess; and means attached to each stem in said recess holding such stems against movement in one direction out of said perforation.
4. A fuse cartridge comprising a body having a recess in its side; a disc disposed with 25 a fuse wire space between a side of the disc and an adjacent end of the body; and a thin member attached to the disc and loosely extending into the body with a portion of said thin member engaging said body limiting the 30 movement of the disc away from such body.

In testimony whereof, I have signed this specification, this 30th day of November, 1918.

THOMAS COLSON.
